CLAIM

The ornamental design for a wearable fishing tackle box, as shown and described.

DESCRIPTION

FIG. 1 is a top perspective view of the wearable fishing tackle box;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

Features illustrated in the various drawing figures which are depicted using broken-lines form no part of the claimed design.
